UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

METAL-SUPPLYING DEVICE.

1,418,418.

Specification of Letters Patent. Patented June 6, 1922.

Original application filed October 12, 1917, Serial No. 196,846. Divided and this application filed May 16, 1918, Serial No. 234,880. Renewed December 7, 1921. Serial No. 520,691.

To all whom it may concern:

Be it known that I, HENRY A. WISE Wood, a citizen of the United States, residing at New York, in the county of New York 5 and State of New York, have invented a new and useful Metal-Supplying Device, of which the following is a specification.

This is a division of my patent on a mold for stereotyping and means for supplying 10 metal thereto, Serial No. 790,071 filed Sept. 16, 1913, patented May 21, 1918, No. 1,266,740.

This invention relates to stereotyping apparatus, particularly of that kind in which the parts are operated by power such, for example, as shown in my application, Serial 15 No. 726,239, filed October 17, 1912. (Renewed Oct. 18, 1919, Serial 330,520) Patent No. 1,341,608, of May 25, 1920. I do not claim herein the subject matter thereof.

20 The principal objects of the invention are to provide a construction for this purpose with improved means for delivering cast plates, discarded tails and pigs of metal into the melting pot timed with respect to the 25 operation of the pump so as to keep the supply proportionate to the amount of metal discharged; to provide for moving the tails on their straight edges throughout their course of travel after they are severed; to 30 provide the gravity chute down which they slide with projections so placed as to turn the tails around while still in the chute; to provide improvements in the elevator for moving the tails up to the top of the metal 35 receiving pot; and more specifically to provide a double chain elevator and a guide for the tails therein.

The invention also involves improvements in the details of construction of these various 40 parts as will appear hereinafter.

Reference is to be had to the accompanying drawings in which

Fig. 1 is a side elevation of a portion of a stereotype casting apparatus, showing the 45 application of a preferred embodiment of this invention thereto.

Fig. 2 is an end view of the same with the melting pot in section to show interior construction.

50 Fig. 3 is a plan of the mechanism for operating the parts.

Fig. 4 is an end view of the portion of the mechanism for feeding metal to the melting pot, and

Fig. 5 is a sectional view on the line 5—5 thereof.

The invention is shown as applied to a stereotype plate casting machine like that shown in my co-pending application for patent on a machine for casting and delivering curved stereotype printing plates, filed on the 16th day of September 1913, Serial No. 790,070, patented December 3, 1918, No. 1,286,479.

Referring first to Figs 1 and 2, it will be 65 seen that a frame 10 is shown on which is a vertical upright core 11, a movable segmental back 12 and a melting pot 31 for supplying the pot with metal.

For the purpose of operating the parts a 70 motor 40 is shown operating a main shaft 41 in any desired way. This shaft in turn preferably operates the mold, pump and finishing mechanism.

Also connected with the main shaft 41, I 75 have shown a shaft 44 provided with a handle 45 for rotating the parts by hand and a shaft 46 connected to operate a shaft 47 having right and left worms 48 thereon to operate the elevator as will appear herein- 80 after.

On the cam shaft 42 is a cam 50 which operates a cam roll 51. This roll is mounted on one arm of a two-branched lever 52 which is pivoted to swing loosely on a shaft 53 supported by the frame. The other arm of this lever is connected by a stud 54 with an arm 55 also pivoted loosely on the shaft 53 and pivotally connected by a link 56 with a nut 57, which is movably mounted on a lever 58. This lever is keyed to the end of a shaft 59. On the shaft 59 is an arm 70 which by a link 71 is connected with a piston rod 72 to the bottom of which is secured the piston 32.

95 For the purpose of feeding the melting pot with metal the following mechanism is provided. On the frame is a chute 80 for receiving the tails T which are severed from the plates by the finishing mechanism (not shown). While being finished the plates P 100 are held on the inclined finishing arch or

support 79. The tails T slide down this chute in the position indicated at the top of Fig. 4 on their straight edges.

One advance corner of each one engages 5 a projection 81 on one lower side of the chute. This causes the tail to be turned around a quarter of a turn so that one of the straight edges is foremost. Then in this position it slides down an incline 82 which 10 forms a part of the chute and which is at an angle to the chute 80, so as to be less abrupt. At the bottom of this incline one advance corner engages a projection 83 on the same 15 side, as indicated in dotted lines in Fig. 4. This causes it to turn again so that one of its curved edges is foremost. Thus it has been turned half way round end for end. Then it slides by gravity over an incline 84 into a conveyor by a fixed plate 88 which 20 turns it to bring its straight edges parallel with the conveyor.

The conveyor is shown as located in an inclined casing 85 provided with two 25 separate bottoms 86 in the plane of the incline 84.

The conveyor is shown as comprising two 30 endless chains 87 which are operated by the two worms 48 and worm wheels 98. The outer strands of the chains pass upwardly 35 on the outsides of the bottoms 86 and the inner strands pass downwardly between these bottoms.

The two chains are provided with projections 89, kept in registration and so arranged 35 that two of these projections pass upwardly on the outer strands together. Therefore, they engage the two edges of the plate and cause the plate to travel upwardly on its straight edges to the top of the conveyor 40 by which it is dumped over into the melting pot. The chains pass over sprocket wheels 90 and 90^a, those at the top located over the melting pot.

The projections on the inner strands of 45 the chains coming down at the center do not interfere with the ascent of the tail as they come within its concavity. It will be understood, of course, that these chains can be used to elevate used plates placed in them 50 by hand and in practice the chains are run at such a speed that these plates can be put in alternately with the tails.

For the purpose of elevating pigs of 55 metal, the casing is provided with a longitudinal projection 91 along one side of the bottom. This forms with the side wall of the casing, a passage way along which the pigs are elevated by one chain.

Although I have illustrated and described 60 only a single embodiment of the invention, I am aware of the fact that many modifications can be made therein by any person skilled in the art without departing from the scope of the invention as expressed in 65 the claims, therefore I do not wish to

be limited to all the details of construction herein shown and described, but what I do claim is:—

1. The combination with an inclined support for castings, and a pot for supplying metal to the mold in which the plates are cast, of means for delivering the severed concave castings from said inclined support by gravity on their straight edges turning them part way around therein while still 75 resting on their straight edges and elevating them into the pot.

2. The combination with a receiving pot, of an endless chain for delivering metal pigs thereto, a casing in which said chain 80 is located, and a projection along the bottom of the casing and spaced from the side walls thereof near the descending strand of the chain and between the two strands forming a channel with the side wall for pigs of 85 metal while being moved upwardly by the chain.

3. The combination with a receiving pot, of an elevator for delivering metal thereto comprising a pair of endless chains having 90 all four strands in the same plane, means for moving the outer strands of said chains upwardly toward the pot at equal speeds, and projections on said chains in registration with each other for engaging the metal 95 pieces to be elevated.

4. The combination with an inclined conveyor delivering upward, of an inclined bottom therefor between the strands of the conveyor, and a chute having an inclined bottom in the same plane as the inclined bottom of the conveyor delivering downwardly to the bottom of the conveyor. 100

5. The combination with an inclined conveyor, of an inclined bottom therefor between the strands of the conveyor, and a chute having an inclined bottom in the same plane as the inclined bottom of the conveyor, and having means for delivering curved tails on its inclined bottom in a predetermined position. 105

6. The combination with an inclined conveyor, of an inclined bottom therefor between the strands of the conveyor, and a chute having an inclined bottom in the same plane as the inclined bottom of the conveyor, having means for delivering curved tails on its inclined bottom in a predetermined position, and a support for the tails at the top of said chute. 110

7. The combination with an elevator for the tails of stereotype printing plates, of an inclined chute for delivering the tails there to, said chute having a projection extending inwardly from one side thereof for engaging the edge of a descending tail and turning the tail around in the chute. 125

8. The combination with an elevator for the tails of stereotype printing plates, of an inclined chute for delivering the tails 130

thereto by gravity, said chute having a projection extending inwardly from one side thereof for engaging the corner of a descending tail and turning the tail around in the 5 chute, and a second projection below the first for turning the tail around further.

9. An inclined chute for delivering severed stereotype plate tails having a floor on which the edges of the tails rest and having a 10 projection extending inwardly from one side thereof for engaging the corner of a descending tail and turning the tail around on the floor, and a second projection below the first for turning the tail around further on 15 the floor, whereby the tails rest on the same edges all the time.

10. A chute having a continuous inclined floor for receiving and delivering severed stereotype plate tails having a fixed projection extending inwardly from one side thereof for engaging the edge of a descending tail and turning the tail around in the chute on its surface which rests on said floor.

11. A continuous chute for delivering 25 severed stereotype plate tails having means for turning the tails around end for end while descending in the chute and while moving along in substantially a straight line therein.

30 12. The combination with an elevator, of a chute for delivering hollow semi-cylindrical articles thereto, and means comprising a projection on the side for ensuring that such articles shall all be presented by the chute

to the elevator, in a position resting on 35 their opposite straight edges and with said edges located parallel to the direction of motion of the elevator.

13. In an elevator, the combination of two 40 endless chains cooperating with each other to support the opposite edges of an article, a casing in which said chains are located, and a projection along the bottom of the casing near the descending strand of one chain forming a channel with the adjacent side 45 wall for guiding a smaller article so that it can be moved upwardly by one chain.

14. An elevator for delivering metal comprising a pair of endless chains with all 50 four strands in the same plane, means for moving the outer strands of said chains upwardly at equal speeds, and projections on said chains in registration with each other for engaging the metal to be elevated.

15. In a conveying device the combination 55 of an endless chain arranged at an inclination for delivering upwardly, a casing in which said chain is located, and a guide along the bottom of the casing at a distance from the side walls thereof located between 60 the two strands of the conveyor, and forming a channel with the side wall near the assembling strand for guiding articles while being moved upwardly by the chain.

In testimony whereof I have hereunto 65 affixed my signature.

HENRY A. WISE WOOD.
